UNITED STATES PATENT OFFICE.

BENJAMIN H. SNAVELY, OF BRUNNERSVILLE, AND THOMAS H. KELLER, OF LITITZ, PENNSYLVANIA.

CIGAR-MACHINE.

SPECIFICATION forming part of Letters Patent No. 768,777, dated August 30, 1904.

Application filed January 9, 1899. Serial No. 701,601. (No model.)

To all whom it may concern:

Be it known that we, BENJAMIN H. SNAVELY, residing at Brunnerville, and THOMAS H. KELLER, residing at Lititz, in the county of Lancaster, State of Pennsylvania, citizens of the United States, have invented certain Improvements in Cigar-Machines, of which the following is a specification.

This invention relates to improvements in that class of devices designed for spreading the wrappers of cigars as said wrappers are drawn into a pocket to be rolled around the fillers; and the object of this invention is to employ brushes for so spreading the wrappers.

The invention consists in the construction and combination of the various parts, as hereinafter fully described, and then pointed out in the claims.

This invention is shown and described, but not claimed, in Letters Patent of the United States No. 617,366 for an improvement in cigar-machines, issued to us on the 10th day of January, 1899.

The invention is illustrated in the accompanying drawings, which form a part of this specification, and in which—

Figure 1 is an elevation of the front of a portion of a cigar-machine embodying our improvements, wherein the frame carrying the spreading-brushes is elevated to show the various parts in the positions occupied thereby, when a wrapper is to be put in place to be rolled around the filler of a cigar; and Fig. 2, a top plan view showing the parts of the machine in the same position. Fig. 3 is a front perspective view wherein the frame carrying the spreading-brushes is lowered to show the various parts in the positions occupied thereby after a wrapper is secured in place to be rolled around the filler of a cigar; Fig. 4, a rear elevation of the parts occupying the same positions as shown in Fig. 3, and Fig. 5 a vertical section on broken line 5 5 of Fig. 4.

Similar letters and numerals indicate like parts throughout the several views.

Referring to the details of the drawings, A indicates the stationary platform of a cigar-machine in which are two longitudinal slots *a* and *a'*.

In front of platform A are arranged a series 5^c of five rollers *b*, *b'*, *b²*, *b³*, and *b⁴*, whereby is formed a longitudinal pocket in which the bunches or fillers are placed to have the wrappers applied thereto, as is usual.

For the purposes of this specification the 55 end of the machine toward which the tuck end of the cigar is formed will be termed the "tuck" end and that at which the head of the cigar is formed the "head" end.

On platform A is a reciprocating table D, 60 that moves thereon longitudinally of the rollers. This reciprocating table is actuated through a vertically-disposed shaft D', extending up through slot *a* of platform A and through an opening in a horizontally-disposed 65 lug 2 on the tuck end of the reciprocating table, through which connection-shaft D' imparts motion to said table.

On the upper end of shaft D' is a bevel-gear *d*, located somewhat above reciprocating 70 table D.

On the end of reciprocating table D toward the tuck end of platform A are arms *d'*, Figs. 3, 4, and 5, wherein is journaled the hinge-rod F of a frame carrying a flat brush for 75 pressing a cigar-wrapper to table D as said wrapper is drawn between the rollers and beneath circular brushes for spreading the same, which circular brushes are also carried by said frame. This frame has a horizontal bar 80 F', disposed parallel with hinge-rod F, and on said horizontal bar are lugs *f*, wherein hinge-rod F is secured.

On the side of horizontal bar F' opposite lugs *f* are formed arms F² F³, Fig. 2. In 85 bearings *f'* on the free ends of arms F² F³ is journaled an approximately horizontal shaft F⁴, having on its front end outside of the adjacent arm F³ a circular brush F⁵ and on the opposite end outside of arm F² a gear-wheel 90 F², and at one side of and below shaft F⁴ is a shaft F⁶, having on the end journaled in arm F² a gear-wheel F⁷, that meshes with gear-wheel F². From arm F² shaft F⁶ is inclined toward the tuck end of the machine and carries on the extremity of the end journaled in arm F³ and outside of and lapping brush F⁸ a circular brush F⁹. Where brushes F⁵ and F⁷

lap each other they are separated by a vertical plate 3, secured to arm F³, and which prevents interference between said brushes. On shaft F⁶ is a bevel-gear f⁴, adapted to mesh 5 with bevel-gear d of vertical shaft D' when said gear-wheel f⁴ is in an operative position, as shown in Fig. 5.

Extending over shafts F⁶ and F⁴ is a curved arm F⁸, having lugs f⁵ on its lower end, 10 through which it is connected with hinge-rod F. The upper end of said arm F⁸ extends beyond shaft F⁴ and has secured thereto the lip f⁶ of a depending rod F⁹ to a tongue f⁷, on the lower end whereof is secured a horizontally-disposed brush F¹⁰, which when the parts are in an operative position presses the wrapper upon reciprocating table D and maintains the same as it is drawn from said table in proper relation to the pocket formed by rollers b b⁴.

Rigidly secured on hinge-rod F is a lever, (see Figs. 1, 3, and 4,) one arm, F¹¹, whereof extends upward and toward shafts F⁶ and F⁴ and which has on its free end a weight F¹². 25 The other arm, F¹³, of said lever extends downward through slot a' of platform A and through it the brush-carrying frame is automatically thrown up by a mechanism not herein shown or described to permit a wrapper to be placed 30 on the reciprocating table D in position to be drawn between the rollers before described.

In operating, the brush-carrying frame being raised so as to uncover the reciprocating table D and the whole length of the entrance 35 to the pocket formed by said rollers b b⁴, as seen in Figs. 1 and 2, the wrapper is put in place on said table, as shown by broken lines W, with the tuck end of the same covering the tuck end of the bunch or of the fillers in 40 said pocket and then said wrapper is secured in position by lowering the brush-carrying frame, so that the brushes secure the wrapper in place. As the wrapper is drawn into said pocket brush F¹⁰ presses the same down on 45 reciprocating table D and guides it in the proper direction as it passes from said table, while brushes F⁵ and F⁷ spread said wrapper. The brush-carrying frame is raised from or lowered into an operative position by hand 50 by grasping weight F¹², or it may be raised or lowered in any other convenient way, automatically or otherwise. Reciprocating table D is actuated to move over stationary platform A and lengthwise of the roller-pocket 55 through vertical shaft D', which travels back and forth through slot a, revolving at the same time in such manner as to impart rotary motion to shafts F⁴ and F⁶ when the brush-carrying frame is in operative position, 60 the lever F¹¹ F¹³ at the same time traveling back and forth through slot a'. At the head end thereof slot a' curves somewhat from slot a and toward the roller-pocket. This tends to draw lever F¹¹ F¹³ slightly behind shaft 65 D' and to turn table D and draw the front

thereof somewhat toward said pocket, changing the direction of the feed of the wrapper to the bunch or filler being rolled therein in said pocket, thus aiding in giving the desired taper to the head of the cigar. To permit 70 this slight change in the relative positions of shaft D' and the lever F¹¹ F¹³, said shaft D' has sufficient play in slot a to allow it to tilt slightly.

We do not confine ourselves to the particular construction of the actuating mechanism, nor to that of the stationary platform and reciprocating table herein shown and described, as they do not form any part of this invention, and it is obvious that many changes may 80 be made therein without departing from the principle and scope of our invention.

Having thus described our invention, what we claim as new, and desire to secure by Letters Patent, is—

1. In combination, a table, mechanism for rolling a wrapper about a filler, reversely-revoluble disk-like brushes disposed in different planes approximately parallel with said rolling mechanism, and means for revolving 90 said brushes, for the purpose specified.

2. In combination, a table, mechanism for rolling a wrapper about a filler, reversely-revoluble disk-like brushes having their axes approximately in the same horizontal plane, 95 the disk-like brushes being approximately parallel with said rolling mechanism, and means for revolving said brushes, for the purpose specified.

3. In combination, reversely-revoluble circular brushes having their peripheries lapping the one over the other, a table, and means for revolving said brushes, for the purpose specified.

4. In combination, reversely-revoluble circular brushes disposed in different planes and having their peripheries lapping the one over the other, a table, and means for revolving 105 said brushes, for the purpose specified.

5. In combination, reversely-revoluble circular brushes having their peripheries lapping the one over the other, a plate interposed between the lapping portions of the brushes, a table, and means for revolving said brushes, 110 for the purpose specified.

6. In combination, reversely-revoluble circular brushes disposed in different planes and having their peripheries lapping the one over the other, a plate interposed between the lapping portions of the brushes, a table, and means for revolving 120 said brushes, for the purpose specified.

7. The combination, in a cigar-machine, of a table, mechanism for rolling a wrapper about a filler, means for pressing a wrapper 125 to the table as the same is drawn therefrom to be rolled around the filler, reversely-revoluble circular brushes disposed in different planes between the table and the rolling mechanism and longitudinally of said mechanism 130

for rolling the wrapper about the filler, and means for revolving said brushes, for the purpose specified.

8. The combination, in a cigar-machine, of a table, mechanism for rolling a wrapper about a filler, means for pressing a wrapper to the table as the same is drawn therefrom to be rolled around the filler, reversely-revoluble circular brushes located between the table and the rolling mechanism and having their peripheries lapping the one over the other, and means for revolving said brushes, for the purpose specified.

9. The combination, in a cigar-machine, of

a table, mechanism for rolling a wrapper about a filler, reversely-revoluble circular brushes disposed in different planes between the table and the rolling mechanism and having their peripheries lapping the one over the other, a plate interposed between the lapping portions of the brushes, and means for revolving said brushes, for the purpose specified.
